SEWING MACHINE

Thor Gunnar Frankert, Stockholm, Sweden

Application April 20, 1945, Serial No. 589,329
In Sweden March 24, 1944

9 Claims. (Cl. 112—105)

1

The present invention relates to a device in sewing machines, particularly in the ready-made-clothing industry, for automatically sewing on hooks or eyes to ribbons for corsets, for example. As a matter of fact, there are machines for this purpose but they are expensive, complicated and not quite reliable of service. Thus, it has proved difficult to obtain exact distances between the hooks or eyes on the ribbon, which is very important because a few fractions only of a millimeter cause incorrect distances between the sewed-on hooks and eyes on the respective ribbons. This is a great disadvantage, because the error is often not discovered until the articles are finished, expensive adjustments being thus necessary. The device according to this invention eliminates these inconveniences.

The invention is substantially characterized by the fact that it consists of two disks rotatably mounted on a common shaft and resting against one another, the said disks being, by the actuation of a rod guided by an eccentric sheave on the sewing machine, adapted to rotate at a certain angle, the two disks being moreover provided with cooperating carrying and locking devices for the hook or eye, which in the initial position of the disks is adapted to be automatically fed on to the disks from a magazine and, simultaneously with the rotation of the disks, be moved to the sewing position on the ribbon, which is fed quite independently in a per se known manner so that exact distances between the sewed-on hooks or eyes are obtained.

An example of an embodiment of the invention is illustrated on the accompanying drawing. All the figures show the device after the hook or eye has been moved to the sewing position.

Fig. 1 shows a top view of the device. Fig. 2 shows the device from the end, i. e. in the longitudinal direction of the sewing machine and from the inside thereof. Fig. 3 shows the device partly in section viewed from the side, i. e. at right angles to the longitudinal direction of the sewing machine.

According to the drawing, the reference numeral 1 indicates the foot plate of the sewing plate, in which is provided a groove 2 with rails 3 and 4 for guiding the ribbon. The said ribbon is fed by known feeding devices not shown.

The hooks or eyes are placed in a row in a magazine, preferably consisting of four parallel rods 5. At the lower end of the magazine there is a discharge device of known kind. It may consist of a springloaded rotary segmental member 6 which is provided with fingers 7 and 8 on the

2

underside. The said fingers are adapted to carry the hook or eye in the magazine in such a way that, when the protruding portion 9 of the member 6 is actuated so that the member is turned, a hook or eye is released while the one lying above is stopped. For the sake of simplicity the discharge device is shown from above in Fig. 1, although in reality it has an inclined position, as will be seen from Fig. 2. The magazine shown on the drawing is particularly intended for hooks. When only eyes are used, the magazine has a vertical position.

The hooks or eyes are moved from the discharge device of the magazine to the sewing position on the ribbon by means of the following device. Two disks 11 and 12 are rotatably mounted on a pin 10. The lower disk 11 has an outwardly projecting segment-shaped flange provided at one end thereof with a recess 13 suited to the hook or eye and somewhat sunk in the flange. The disk 11 is further provided with two pins 14 and 15, each of which enters its individual slot 16 and 17 in the upper disk 12. By this arrangement the disks are rotatable relatively to one another a distance corresponding to the length of the said slots. By means of a sleeve 18 the upper disk 12 is movable around the shaft 10. This sleeve 18 carries in its turn another sleeve 19 rotatable around the same. The sleeve 19 is provided with a presser, or hook retaining device for the hook or eye, consisting of a pawl 20 turnably mounted on an ear 21 fixed on the sleeve 19. A spring 22 tends to hold the pawl 20 in depressed position.

An arcuate rib 23 having a higher step and a lower step connected by an inclined cam surface is mounted on the upper surface of the disk 12. In the position shown the pawl rests on the lower step of the rib 23 and when the disk 12 begins its clockwise movement, the pawl 20 glides on to the upper step of the rib 23 and is raised from the hook or eye. The sleeve 19 is provided with an arm 24 screwed into the same, the said arm resting against the pin 14 fixed in the lower disk 11 by a spring 25, one end of which is fixed to the arm 24 and the other to the pin 15.

On the upper disk 12 there is further located a pin 26 which is adapted to actuate the protruding portion 9 of the segmental member 6. By means of a pivot 27 located on the disk 12 the disks are via a rod 28 connected with an eccentric sheave on the sewing machine, the said sheave imparting to the rod a reciprocal motion and thus to the disks oscillatory motion through a certain angle.

The lower disk 11 is provided with a per se

known brake device 29. By this device it is obtained that when returning from the sewing position the lower disk 11 is retained in its position until the disk 12 has rotated a length corresponding to the slots 16 and 17, whereafter the disk 11 is brought along in the rotary movement of the disk 12. During this movement of the disk 12 relatively to the disk 11 the pressure of the pawl 20 against the hook or eye is released by the pawl gliding on to the upper step of the rib 23 as mentioned above, whereafter the two disks return together to the initial position. In this position the disk 12 has the same range of movement in the slots 16, 17 as in the sewing position. The lower disk 11 is still locked by the brake device 29, and therefore, after the hook or eye has fallen into the recess 13, the upper disk 12 turns and allows the pawl 20 to exactly lock the hook or eye by the rib 23 being turned forwards prior to the disks being moved together to the sewing position.

The device operates as follows:

On turning of the disks 11 and 12 in counterclockwise direction, the stop 26 actuates the protruding portion 9 of the segmental member 6 so that the latter turns a corresponding distance and drops a hook or eye from the magazine into the recess 13 of the segmental flange on the lower disk 11. Next, the rod 28 rotates the disks through a certain angle in counterclockwise direction so that the hook or eye comes to the sewing position shown in Fig. 1. As soon as this movement begins, the pawl 20, which serves as pressure foot, glides down from the upper step of the rib 23 and presses against the hook or eye in the recess 13 and thus holds the same until it comes to the sewing position. This downward gliding of the pawl 20 is caused by the rotation of the disk 12 relatively to the disk 11 a distance corresponding to a slot length. During the clockwise rotation of the disks towards the feeding position the disk 12 first rotates a distance corresponding to the length of the slots 16, 17, the pawl 20 gliding on to the upper step of the rib 23 and liberating the hook or eye. Thereafter the disk 12 carries along the lower disk 11 in the rotary movement by means of the pins 14 and 15. The pawl 20 accompanies in raised position the disk 11 due to the pull exerted by the spring 25 upon the pin 24 and the sleeve 19. The process is then repeated from the initial position at the feeding device. The feeding of the ribbon takes place quite independently during the rotary movement, and therefore the longest possible time is obtained for the operation of the disks during the said movement.

More specifically with respect to the rotary movement of the disks 11 and 12, in sewing position, Fig. 1, the pins 14 and 15 lie at the right hand ends of the slots 16 and 17 in the disk 12. During clockwise movement to the feeding position, the disk 12 first rotates a distance corresponding to the length of the slot 16 or 17, the pawl 20 gliding on to the upper plane of the projection 23 and liberating the hook or eye. Thereafter the disk 11 is carried by the disk 12. During this operation the pins 14 and 15 are at the left hand ends of the slots 16 and 17. At counterclockwise movement to the sewing position the disk 12 first rotates a distance corresponding to the length of the slot 16 or 17, the pawl 20 gliding on to the lower plane of the projection 23 and pressing the hook or eye in the recess and holds the same until it comes to the sewing position. These movements are facilitated by the fact that the disk 11 is provided with a brake device 29.

As is clear from the above, the device according to the invention is very simple with regard to its construction and mode of operation. Due to the compact construction which is based on a rotary movement, a great exactness of the mode of operation is obtained, all play or the like caused by levers and rods for example, being quite eliminated.

Having now described my invention, what I claim as new and desire to secure by Letters Patent is:

1. In a sewing machine for automatically sewing small objects, such as hooks or eyes, at spaced intervals to a length of fabric material, a mechanism 15 for placing the objects to be sewed on in predetermined time intervals on the material following successive feeding movements thereof by the sewing machine, said mechanism comprising a first member including an object holder and oscillatable between a feeding position in which said object holder is located to receive an object and a sewing position in which said object holder is located on the material to which the object is to be sewed, a second member oscillatable parallel to said first member through a distance exceeding that between said two positions, means connecting said two members, for limited relative oscillatory movement, means for oscillating said second member in a predetermined sequence, a 20 pressure foot connected to said first member for movement therewith between said two positions and movable towards and away from said object holder, and means including a cam on said second member cooperating with a portion of said 25 pressure foot to move the latter away from said object holder when said second member starts its movement in the direction from said sewing position towards said feeding position and to move said pressure foot towards said object holder when said second member starts its movement in the opposite direction.

2. A mechanism as claimed in claim 1, including brake means to prevent said first member from moving with said second member during 45 the initial phase of each movement of the latter.

3. In a sewing machine for automatically sewing small objects, such as hooks or eyes, at spaced intervals to a length of fabric material, a mechanism 50 for placing the objects to be sewed on in predetermined time intervals on the material following successive feeding movements thereof by the sewing machine, said mechanism comprising two superposed disks oscillatable about a common vertical axis through a certain angle 55 in either direction, one of said disks including an object holder which moves on oscillation of said disk between a feeding position and a sewing position, means connecting said two disks for limited relative rotation, means for oscillating the 60 other disk about said axis through a distance exceeding that between said two positions, a pressure foot connected to said first disk for movement therewith between said two positions and movable toward and away from said object holder, and means including a cam on said second disk cooperating with a portion of said pressure foot to move the latter away from said object holder when said second disk starts its movement in the direction from said sewing position 65 toward said feeding position and to move said pressure foot toward said object holder when said second disk starts its movement in the opposite direction.

4. A mechanism as claimed in claim 3, in which 70 said means connecting said two disks include at

75 said means connecting said two disks include at

least one pin projecting from one of said disks parallel to the axis thereof through an arcuate slot in the other disk.

5. A mechanism as claimed in claim 3, in which the disk including the object holder is disposed below said second disk and said object holder comprises a segmental flange on said lower disk formed with a recess at one end thereof to receive the object to be moved from the feeding position to the sewing position.

6. A mechanism as claimed in claim 3, in which the disk including the object holder is disposed below said second disk, the latter having an upwardly projecting hub, said pressure foot including a sleeve rotatably mounted on said hub of said upper disk, and a spring-actuated pawl pivoted to said sleeve.

7. A mechanism as claimed in claim 3, in which said disk including the object holder is disposed below said second disk, the latter including an upwardly projecting hub, said means connecting the two disks including two pins projecting upwardly from said lower disk parallel to the axis thereof through arcuate slots in the upper disk, said pressure foot including a sleeve rotatable about said hub of the upper disk, a spring-actuated pawl pivoted to said sleeve, an arm radially projecting from said sleeve, and a spring connecting said arm with one of the pins projecting from said lower disk through the slots in said upper disk.

5

10

15

20

25

ated pawl pivoted to said sleeve, an arm radially projecting from said sleeve, and a spring connecting said arm with one of the pins projecting from said lower disk through the slots in said upper disk.

8. A mechanism as claimed in claim 3, in which the disk including the object holder is disposed below said second disk, the latter including an upwardly projecting hub, said pressure foot including a sleeve rotatable about said hub, a spring-actuated pawl pivoted to said sleeve and means connecting said sleeve to said lower disk for movement therewith, said cam being constituted by an arcuate rib on the upper surface of said upper disk including a lower step, a higher step, and an inclined cam portion connecting said two steps and arranged for cooperation with a portion of said pawl.

9. A mechanism as claimed in claim 3, including brake means to prevent said first disk from moving with said second disk during the initial phase of the rotation of the latter in either direction.
